CLAIM

The ornamental design for a pavement crack sealer machine, as shown and described.

DESCRIPTION

FIG. 1 is a top perspective view of a pavement crack sealer machine showing our new design;

FIG. 2 is a right side elevational view thereof, the left side being a mirror image;

FIG. 3 is a top plan view thereof;

FIG. 4 is a bottom plan view thereof;

FIG. 5 is a front elevational view thereof; and

FIG. 6 is a rear elevational view thereof.

The hose and support bracket in FIGS. 1-6 are broken away for ease of illustration and are understood to represent indeterminate length.
